ABSTRACT: This disclosure relates to a partition formed from "two-sided" paperstock material wherein a blank of two-sided material is folded to form a longitudinal partition panel and at least a single transverse partition panel at each side of the longitudinal partition panel. A portion of the blank at each side of the longitudinal partition panel is struck to form a shock-absorbing flap, and each flap is folded upon its adjacent transverse partition panel with the same side of the two-sided material in face-to-face bonded relationship whereby the bond strength is thereby materially increased as opposed to the bond strength which would exist if opposite sides of the shock-absorbing flap and the transverse partition panel were bonded together.

TWO-SIDED BOTTLE CARRIER PARTITION

Paperstock material never has identical appearance and surface characteristics on both sides of the sheet, and this difference in appearance of the two sides of paper is referred to as "two sidedness." All paperstock materials have a certain amount of two sidedness and in general the top side of the paper is smoother and has a closer formation than the wire side, but not always.

Two sidedness may be an actual structural two sidedness due to greater concentration of size, pigment or fines on one side of the sheet, or it may be an optical two sidedness caused by a difference in the finish or reflection on the two sides of the sheet. Most paperstock material, and particularly thicker paperstock material of the type used to form bottle or can carriers, cartons, wraparound carriers or the like, show definite two sidedness in regard to fibrous composition. This is usually manifested in a preponderance of larger fibers on the wire side and a preponderance of finer, smaller fibers on the felt side.

Two sidedness may be caused by one or more of the following factors:

1. loss of fine fibers through the wire before a mat of the larger fibers is laid down;
2. slower settling of the fine fibers, due to their reduced specific gravity and hydrodynamic resistance, with the result that a higher percentage of fines are deposited on the top side of the sheet;
3. removal of the finer fibers from the underside of the wet sheet after formation due to the action of the table rolls and the suction boxes.

Increased machine speeds have over the years also added to an increased amount of two sidedness.

It is known that the effect of greater concentration of fine material on the felt side results in an increase in the strength of the paperstock, an increase in smoothness, and the improved printing qualities on this side of the paper. This is obviously the desirable side upon which to print such things as the identification of the manufacturer or producer of the product, as is typical of wraparound-type carriers, but it is also the least desirable side to apply adhesive since the bond strength is reduced due to the relatively nonporous nature because of the concentration of fine material on the felt side, as opposed to the wire side which has a greater bond strength because of the lesser amount of fine material.

Though two sidedness is ordinarily undesirable in writing paper, it is intentionally sought after in the carton and carrier manufacturing industry for reasons of economy and improved products. For example, paperboard made on a cylinder machine is often made intentionally two sided by using different grades of stock in the liner and filler plies. In this way, cheaper stock can be used in the filler and more expensive stock used in the outside plies, with the latter again being more desirable for printing purposes and the former for adhesive purposes.

Recognizing the desirability of using such two-sided paperstock for carriers, cartons and partitions thereof, and also recognizing the desirability of using one side of the paperstock material for one particular purpose and an opposite side thereof for another, it is a primary object of this invention to provide a novel partition constructed from a blank of two-sided material folded to form a longitudinal partition panel, a plurality of transverse partition panels at each side of the longitudinal partition panel, and a plurality of shock-absorbing panels struck from the material of the blank to provide multiply thicknesses to prevent article damage between adjacent compartments with the shock-absorbing flaps being adhesively bonded upon adjacent portions of the blank with one and the same side of the material in face-to-face bonded relationship.

It is a further object of this invention to provide a novel partition of the type described wherein the bonds are formed across the more porous side of the two-sided blank.

A further object of this invention is to provide a novel partition of the type heretofore described wherein a pair of trans-

verse partition panels at each side of the longitudinal partition panel are joined to each other by a connecting panel, and each connecting panel has struck therefrom a shock-absorbing flap which is likewise folded upon one of the transverse panels and is bonded thereto between the more porous side of the blank.

With the above and other objects in view that will hereinafter appear, the nature of the invention will be more clearly understood by reference to the following detailed description, the appended claimed subject matter, and the several views illustrated in the accompanying drawings.

In the Drawings:

FIG. 1 is a top plan view of a two-sided blank for forming a partition in accordance with this invention, and illustrates the blank with its smoother, least porous and least bondable side uppermost.

FIG. 2 is a top plan view of the blank of FIG. 1, and illustrates the blank after being partially folded.

FIG. 3 is an edge view of the blank of FIG. 2 looking from bottom to top, and more clearly illustrates the manner in which the blank is folded.

FIG. 4 is a fragmentary top perspective view of the partition blank after having been completed and inserted within a carton or carrier.

FIG. 5 is a fragmentary perspective top view similar to FIG. 4, and illustrates the opposite side of the partition and carton.

FIG. 6 is a sectional view taken generally along line 6—6 of FIG. 4, and illustrates the manner in which shock-absorbing flaps are folded out of the planes of longitudinal panels and connecting panels to form multi-ply transverse dividers between centermost and endmost compartments on each side of the longitudinal partition.

FIG. 7 is a sectional view taken generally along line 7—7 of FIG. 6, and more clearly illustrates details of the partition and particularly the two-ply construction of the leftmost transverse divider.

FIG. 8 is a sectional view taken generally along line 8—8 of FIG. 7, and illustrates the manner in which one of the shock-absorbing panels has been pivoted out of the plane of its associated connecting panel.

Reference is first made to FIG. 1 of the drawings which illustrates a blank 10 of "two-sided" paperstock material of the type heretofore described. In view of the "two-sided" nature of the blank 10 and for the purposes of describing the relationship thereof to the formation of a carton or carrier 15, the blank 10 of FIG. 1 has applied to the visible side thereof a plurality of reference characters S1 which represent the smoother side of the blank 10 while the opposite side of coarser more porous material is designated by the reference numeral S2. FIG. 1 illustrates the blank 10 prior to being folded in any manner, and therefore only side S1 is visible.

The blank 10 is provided with three longitudinal partition-forming panels 11, 12 and 13 with the panel 11 being connected to the panels 12, 13 along respective fold lines 16, 17. The panels 11, 12 and 13 include respective carrying-handle portions 18, 20 and 21. The handle-carrying portion 18 includes a pair of rectangular openings 22 while the handle portions 20, 21 each include a pair of openings 23 and a flap 24 joined to the carrying-handle portion by a fold line 25. The flaps 24 are folded in a known manner to overlie the uppermost edges of the openings 22 to permit the carrier 15 to be easily carried.

The blank 10 further includes a pair of transverse compartment-forming panels 26 and 27. The transverse compartment-forming panel 26 is partially formed from the material of the longitudinal panel 12 and includes a first transverse panel 28 joined to the longitudinal panel 12 along a fold line 30, a connecting panel 31 joined to the first transverse panel along a fold line 32 and a second transverse panel 33 joined to the connecting panel 31 along a fold line 34. A terminal panel 35 is joined to the second transverse panel 33 along a fold line 36. A cut line 37 separates the panels 28, 31 from the longitudinal partition panel 12.

A shock-absorbing flap or panel 38 is struck from the material of the connecting panel 31 along a pair of generally parallel cut lines 40, 41 and a sinusoidal cut line 42 therebetween. The shock-absorbing panel 38 is joined to the panel 33 along the fold line 34, and as viewed in FIG. 1 the shock-absorbing panel 38 projects from left to right away from the fold line 34.

Another shock-absorbing panel 43 is struck from the material of the longitudinal partition panel 12 along a pair of parallel cut lines 44, 45 and a generally sinusoidal cut line 46 therebetween. The shock-absorbing panel 43 is likewise joined by the fold line 30 to the first transverse panel 28, and projects away from the panel 28 in a left-to-right direction as viewed in FIG. 1. A connecting panel 47 is also struck from the material of the partition panel 12 along a generally C-shaped cut line 48. The panel 47 is joined to the longitudinal partition panel 11 along the fold line 16 and projects toward the shock-absorbing panel 43 in a right-to-left direction, as viewed in FIG. 1.

The transverse compartment-forming panel 27 is similar in structure to the transverse compartment-forming panel 26 and includes a first transverse panel 50 joined to the longitudinal panel 13 along a fold line 51, a connecting panel 52 joined to the first transverse panel 50 along a fold line 53, and a second transverse panel 54 joined to the connecting panel 52 along a fold line 55. A terminal flap or panel 59 is joined to the second transverse panel 54 along a fold line 56. The panels 50, 52 are formed from the material of the longitudinal panel 13 and are separated therefrom along an upper edge (unnumbered) by means of a cut line 57.

A shock-absorbing flap or panel 58 is formed from the material of the connecting panel 52 by striking along a pair of parallel cut lines 60, 61 joined to each other along a sinusoidal cut line 62. The shock-absorbing panel 58 is joined to the second transverse panel 54 by the fold line 55 and projects from right-to-left, as viewed in FIG. 1. Another shock-absorbing panel 63 is formed from the material of the partition panel 13 by striking along a pair of generally parallel cut lines 64, 65 which are connected by a sinusoidal cut line 66. The shock-absorbing panel 63 is joined to the first transverse panel 50 along the fold line 51 and projects from right-to-left.

A connecting panel 67 is also formed from the longitudinal partition panel 13 by means of a generally inverted C-shaped cut line 68, and is joined to the longitudinal partition panel 11 by the fold line 17. The connecting panel 67 projects away from the fold line 17 in a left-to-right direction.

From the foregoing, it will be noted that the blank 10 is identical to the left of the fold line 16 and to the right of the fold line 17 except for the direction of projection of the panels or flaps 38, 43, 47 as compared to the direction of projection of the respective panels or flaps 50, 63 and 67.

The manner in which the blank 10 is folded to form the partition 10 of the carton 15 of FIGS. 4 through 8 will now be described, it being noted that the stippling in FIG. 1 indicates adhesive applied to the surface S1 of the blank 10.

As is best illustrated in FIG. 3, the shock-absorbing panel 58 is folded out of the plane of the connecting panel 52 along the fold line 55 and the side S2 of the panel 58 is brought into adhesive face-to-face contact with the side S2 of the panel 54. The panel 59 is then overfolded to bring its side S2 into overlying though not adhesive engagement with the side S2 of the panel 54. In this position the panel 59 partially overlies portions of the sinusoidal edge 62 of the panel 58. The panel 50 is then folded along the fold line 51 to bring the side S2 of the panel 50 into adhesive face-to-face contact with the side S2 of the shock-absorbing panel 63. In this position the fold lines 17, 53 are in alignment, as is best shown in FIG. 3.

Adhesive upon the panel 59 secures the same into face-to-face contact with the side S2 of the panel 11.

The shock-absorbing panel 38 is then folded along the fold line 34 and brought into adhesive contact with the side S2 thereof in contact with the side S2 of the panel 33.

The panels 12, 28 and 31 are then accordion folded along the respective fold lines 16, 30 and 32 which brings the side S2 of the panel 28 into adhesive face-to-face contact with the side S2 of the shock-absorbing panel 43. This same folding brings the panel 35 with its side S1 in adhesive contact with the side S1 of the panel 11.

Thereafter the panel 13 is folded along the fold line 17 in the direction indicated by the unnumbered-headed arrow in FIG. 3 which brings the side S2 of the handle-forming portion 21 into adhesive contact with the side S2 of the handle-forming portion 18. This completes the formation of the blank into the partition 10 which can be opened and inserted into a carton in the manner illustrated in FIGS. 4 through 8, to which attention is now directed to more clearly depict the manner in which the panels are adhesively joined to each other and to the carton.

Referring particularly to FIGS. 4, 5 and 6, the two-sided relationship of the various panels and flaps are more clearly depicted upon the erection of the partition 10 and the formation of the two transverse article-receiving compartments 26 and 27.

Referring first to the transverse article-receiving compartment 26, the compartment is formed by the two transverse partition panels 28, 33 and the connecting panel 31. The side S1 of each of the panels 28, 31 and 33 is inside the compartment 26 while the side S2 of each of the panels 28, 31 and 33 forms the outside of the compartment 26. Likewise, the side S1 of the longitudinal partition panel 11 forms the fourth wall of the article-receiving compartment 26.

The shock-absorbing panel 43 when folded in the manner heretofore described along the fold line 30 is moved out of the plane of the partition panel 12 with the side S2 of the shock-absorbing panel 43 being brought into engagement and adhesive contact with the same side S2 of the transverse panel 28. The shock-absorbing panel 43 thereby cooperates with a portion of the transverse panel 28 to form a multi-ply, shock-absorbing transverse divider between articles placed in the compartments at either side thereof.

The folding of the shock-absorbing panel 38 in the manner heretofore described, and indicated by the unnumbered-headed arrow associated therewith in FIG. 6, presents the side S2 of the panel 38 in adhesive contact with the side S2 of the transverse panel 33, likewise again forming a multi-ply, shock-absorbing and reinforcing transverse divider between articles placed in the compartments to either side thereof.

The article-receiving compartment 27 is the reverse of the compartment 26 from the standpoint of the inner and outer sides thereof. That is, the side S2 of the panels 11, 50, 52 and 54 forms the inside of the compartment 27 while the outside is formed by the side S1. Thus the folding of the shock-absorbing panels 63, 58 is the reverse of the folding of the panels 43, 38 in order that the side S2 of the shock-absorbing panel 58 is brought into adhesive contact with the side S2 of the transverse panel 54 and the side S2 of the shock-absorbing panel 63 is brought into adhesive contact with the side S2 of the transverse panel 50, again as best illustrated in FIG. 6.

It will therefore be noted that in both of the article-receiving compartments 26, 27 the more porous and more readily bondable side S2 of the shock-absorbing panels 43, 38, 63 and 58 are brought into adhesive contact with the same side S2 of the respective panels 28, 33, 50 and 54.

Apart from the partition 10, the body of the carton 15 is of a conventional construction, and need not be described in detail except to note that it includes two end panels (unnumbered), two side panels (also unnumbered), and a bottom panel (unnumbered) with the flaps 47, 67 being adhesively secured to the end panels, as shown in FIG. 6, and with the connecting panels 31, 52 being also preferably adhesively connected to the side panels of the carton.

While preferred forms and arrangements of parts have been shown in illustrating the invention, it is to be clearly understood that various changes in details and arrangement of parts may be made without departing from the spirit and scope 75 of this disclosure.

I claim:

1. A partition comprising a blank of two-sided material folded to form a longitudinal partition panel and at least a pair of transverse partition panels at each side of said longitudinal partition panel, portions of said blank at each side of said longitudinal partition panel being struck to form opposite side pairs of shock-absorbing flaps, the shock-absorbing flaps at one side of said longitudinal partition panel being folded outboard upon the associated transverse partition panels with the same side of said material in face-to-face relationship, the shock-absorbing flaps at the other side of said longitudinal partition panel being folded inboard upon the associated transverse partition panels with the same side of said material in face-to-face relationship, means bonding each flap and its associated transverse partition panel to each other to form a multi-ply shock-absorbing transverse divider at each side of said longitudinal partition panel and a terminal end portion of at least one of said shock-absorbing flaps projecting toward said longitudinal partition panel at each side thereof.

2. The partition as defined in claim 1 wherein at least one of said shock-absorbing flaps is formed by striking the portion thereof from the longitudinal partition panel.

3. A partition comprising a blank of two-sided material folded to form a longitudinal partition and a pair of transverse partitions at each side of said longitudinal partition, a connecting panel joining each pair of transverse partition panels remote from said longitudinal partition, each of said pair of transverse partitions and its associated connecting panel in part defining an article-receiving compartment on each side of said longitudinal partition, one side of material defining an exterior surface of one of said compartments, and said one side of material defining an interior surface of the other of said compartments.

4. The partition as defined in claim 3 including a shock-absorbing flap struck from the material of said longitudinal partition, said flap being joined to said longitudinal partition by a fold line, said flap being folded along said fold line out of the plane of said longitudinal partition with said one side of material of said flap in face-to-face relationship with said one side of material of one of said transverse partitions, and means for bonding said flap to said one transverse partition.

5. The partition as defined in claim 4 wherein said flap is disposed internally of its associated article-receiving compartment.

6. The partition as defined in claim 4 wherein said flap is disposed externally of its associated article-receiving compartment.

7. The partition as defined in claim 3 including a shock-absorbing flap struck from the material of one of said connecting panels, said flap being joined to an adjacent transverse partition by a fold line, said flap being folded along said fold line out of the plane of said one connecting panel with said one side of material of said adjacent transverse partition, and means for bonding said flap to said adjacent transverse partition.

8. The partition as defined in claim 7 wherein said flap is disposed internally of its associated article-receiving compartment.

9. The partition as defined in claim 7 wherein said flap is disposed externally of its associated article-receiving compartment.

10. The partition as defined in claim 3 including a first shock-absorbing flap struck from the material of said longitudinal partition and a second shock-absorbing flap struck from the material of the connecting panel of said one compartment, said first and second flaps being folded with said one side of material thereof in face-to-face relationship with said one side of material of one of said transverse partitions of said one compartment and with said one side of material of said connecting panel of said one compartment, respectively.

11. The partition as defined in claim 3 including a first shock-absorbing flap struck from the material of said longitudinal partition and a second shock-absorbing flap struck from the material of the connecting panel of said other compartment,

ment, said first and second flaps being folded with said one side of material thereof in face-to-face relationship with said one side of material of one of said transverse partitions of said other compartment and with said one side of material of said connecting panel of said other compartment, respectively.

12. A blank of the type adapted to be folded to form a partition having a longitudinal partition and a pair of transverse partitions on each side of said longitudinal partition with each pair of transverse partitions being joined by a connecting panel, said blank comprising a sheet of two-sided material, said sheet including a pair of longitudinal partition-forming panels, a fold line joining a transverse compartment-forming panel to each longitudinal partition panel, each transverse compartment-forming panel including a connecting panel between first and second transverse partition panels, a shock-absorbing flap struck from each connecting panel and being joined by a fold line to one of each of said transverse partition panels, and another shock-absorbing flap struck from each longitudinal partition-forming panel and being joined by a fold line to the other of said transverse partition panel.

13. The blank as defined in claim 12 wherein said shock-absorbing panels are arranged in pairs diverted toward each other.

14. The blank as defined in claim 13 including a third longitudinal partition-forming panel connected to and between said pair of longitudinal partition-forming panels.

15. The blank as defined in claim 12 including a third longitudinal partition-forming panel connected to and between said pair of longitudinal partition-forming panels.

16. A carton body comprising a pair of sidewalls, a pair of end walls, and a bottom wall, partition means setting off a plurality of article-receiving compartments in said body, said partition means including at least a pair of longitudinally extending partition walls, said partition walls each being defined by a longitudinal partition panel, a pair of transverse partition panels, and a connecting panel between said pair of transverse partition panels and generally parallel to said longitudinal partition panel, a first shock-absorbing flap struck from each longitudinal partition panel and folded against an adjacent transverse partition panel, and a second shock-absorbing flap struck from each connecting panel and folded against each remaining transverse partition panel.

17. The carton body as defined in claim 16 wherein the shock-absorbing flaps at one side of said longitudinally extending partition walls are outboard of the transverse partition panels on said one side while the shock-absorbing flaps at the other side of said longitudinally extending partition walls are inboard of the transverse partition panels on said other side.

18. The carton body as defined in claim 17 wherein surface portion of the same side surface of said shock-absorbing flaps and said transverse partition panels are in contact.

19. The carton body as defined in claim 17 including another partition wall sandwiched between said pair of longitudinally extending partition walls, and means for securing each remaining transverse partition panel to said another partition wall.

20. The carton body as defined in claim 16 wherein surface portion of the same side surface of said shock-absorbing flaps and said transverse partition panels are in contact.

21. The carton body as defined in claim 20 including another partition wall sandwiched between said pair of longitudinally extending partition walls, and means for securing each remaining transverse partition panel to said another partition wall.

22. The carton body as defined in claim 16 including another partition wall sandwiched between said pair of longitudinally extending partition walls, and means for securing each remaining transverse partition panel to said another partition wall.

23. A partition-forming blank for a carrier body having vertical side and end walls arranged in rectangular plan comprising a pair of similar partition-forming walls, each partition-forming wall including in order and joined together by respec-

tive first, second and third fold lines a longitudinal partition panel, a first transverse partition panel, a connecting panel and a second transverse partition panel, and a shock-absorbing flap struck from each connecting panel with said third fold line defining a hinge for the folding thereof upon an adjacent one of said second transverse partition panels.

24. The partition-forming blank as defined in claim 23 including a shock-absorbing flap struck from each longitudinal partition panel with said first fold line defining a hinge for the folding thereof upon an adjacent one of said first transverse partition panels.
